RADIO COIL WINDING

Application filed September 19, 1929. Serial No. 393,788.

This invention relates to improvements in electrical coils and is directed more particularly to improvements in coils of the solenoid type such as are used in radio apparatus and the like.

5 Solenoid coils, as is well known, comprise tubular supports or cores on which an inductance is formed by winding a wire or wires spirally thereon.

10 Present-day demands require that the number of turns of coils be exact, that the coil be disposed in a certain way on the support in the form of a tube and it is an ordinary requirement that the coil be provided 15 with one or more taps from certain turns thereof.

To provide the taps there are at least two common methods in use which are as follows:—According to one method the coil 20 winding is started at a definite point on the tube and at a predetermined distance from this point is located a round loop receiving opening through the wall of the tube. When the required number of turns of wire have 25 been wound on the tube an instrument is inserted in the tube with its end extending up through the opening so as to hook onto the wire of the particular turn and pull it downwardly and out the end of the tube

30 forming a loop for a tap. This opening of course must be sufficiently large to allow the hook to pass therethrough and is therefore necessarily many times larger than the wire itself. Due to many causes this turn 35 of the wire which it is desired to loop for a tap does not always pass over the center of the opening so that as the wire is pulled downwardly to form the loop there is a tendency of the wire to overlie the axis of the opening. That is, the turn tends to shift. This shifting of the wire causes a separating 40 of the turns and is objectionable for many obvious reasons.

According to the other method a relatively 45 small opening is provided in the wall of the tube which is of a diameter to allow a wire doubled upon itself to pass therethrough. This is located of course as accurately as is possible with reference to the turn which is 50 to be tapped and the tap is formed by looping

the wire from the particular turn outside the work and passing the loop downwardly through the opening. This operation is bothersome and consumes time so that the production is retarded and manufacturing 55 costs increased and there is the further objection that the wire forming the loop tends to kink.

According to the novel features of this invention we overcome the objections and disadvantages referred to above by providing a slot which extends circumferentially of the support for guiding the wire for forming the tap loop and associate therewith a larger opening in communication therewith for receiving a hook for the looping operation. The slot is relatively narrow for a loop wire guiding function only, whereby a particular turn may be looped without the liability of the wire shifting on the tube while the hook 70 opening may be utilized for its function without interfering with the function of the loop slot.

The invention in the form at present preferred will be described in connection with 75 the accompanying drawings, but it will be understood that various changes may be made in the form thereof without departing from the spirit and scope thereof.

In the drawings:

Fig. 1 is a front elevational view of a tubular core having a loop forming slot in the wall thereof.

Fig. 2 is a similar view showing a winding on the tubular core and a loop being formed 85 therein.

Fig. 3 is a side elevational view partly in section to explain certain features of the invention.

Fig. 4 is an enlarged partial sectional view 90 showing the loop opening in the side wall of the support.

Figs. 5 and 6 are fragmentary front elevational views showing modified forms of the loop forming slot, and

Fig. 7 is an enlarged partial elevational view of a tube showing a further modified form of the invention.

Referring to the drawings, the invention will now be described in detail,

A core or support in the form of a tube is represented at S which is adapted to receive a coil winding. If desired this may be threaded to receive the turns of the wire forming the coil and may be of any certain diameter and length to receive any number or arrangement of turns. At the point where a certain turn of a coil winding overlies the support and where it is desired to provide a tap at the particular turn there is provided an elongated loop opening at 2 which extends circumferentially of the support. This as distinguished from the large circular opening of the prior art is relatively narrow and may be in width about twice or three times the diameter of the wire forming the coil winding.

Extending longitudinally of the tube and disposed at a side of the slot there is a hook opening 4 which is in communication with the slot. This may be in various shapes and is intended to permit the passage of a hook therethrough as will later appear. As will be seen, this loop opening or slot provides an edge which extends circumferentially of the supporting tube and functions as a guide for a loop of wire as it is pulled downwardly therethrough.

As in Figs. 2, 3 and 4 a coil C is formed by winding wire on the tube in any usual well known way. For instance, the tube may be rotated and wire W guided thereonto by a guide G while it is tensioned by pressure as it passes through the fingers. The guide and support may be moved relative to one another to obtain the desired lay or pitch of the winding and as the turn to be tapped passes over the slot 2 the tube is held against rotation. A hook H is then passed inside the tube and its forward end slipped up through the opening so that the end may overlie and engage the turn of the winding to be looped for a tap. The hook H is pulled downwardly and out through the tube bringing the wire with it. The wire is tensioned by the pressure of the fingers meanwhile so as to form a loop L. By means of the hook in the loop the loop may be twisted or anchored about a terminal T and when so anchored the support is then rotated to complete the winding of the coil.

The modification of the invention shown in Fig. 5 will now be described. In this form the tubular core is provided with an elongated circumferentially disposed slot 10 as in the former case and a hook receiving angular opening 12 in communication therewith. In Fig. 6 a similar slot 14 is in communication with a circular hook opening 16.

In Fig. 7 there is shown an angular opening 18. In this case the sides 20 of the opening are disposed at right angles to a bisector of the angles 22 between the turn 24 of the coil and the loop forming parts 26 of the loop 28. With this modification of the in-

vention the tendency of a looped turn to move along the sides of the opening is obviated since the angles between the sides of the opening and the wire portions 24 and 26 are equal. In this case it is not necessary for the tapped turn to be located at any particular point relative to the opening.

In all cases the loop opening or slot cooperates with the hook opening to form a combined aperture having its widest part extending circumferentially of the core, while the hook opening extends longitudinally thereof.

From the foregoing it will be observed that we have provided means to facilitate the forming of a loop and means separate therefrom to hold the wire forming the loop and thereby the looped turn against shifting. By the means of all of which we overcome the objections and disadvantages incident to the prior art methods and at the same time effect economy in manufacture as well as increase production and produce coils which are accurate in all respects.

The principles of the invention may be utilized in various ways without departing from the spirit and scope thereof, therefore we do not wish to be limited by the foregoing disclosure but desire to claim the invention as broadly as the law allows.

What we claim is:

1. A support for a tapped inductance comprising in combination, a supporting tube having an opening in the side wall thereof, said opening being formed by a combined loop-slot and hook opening, said loop-slot having a side extending circumferentially of the tube and the hook opening having sides which extend angularly from said slot and longitudinally of said tube.

2. A support for a tapped inductance comprising in combination, a supporting tube having in the side wall thereof a loop-slot and an opening for receiving a hook, the loop-slot including a guiding side edge extending circumferentially of the support and the hook opening including side edges disposed angularly with respect thereto and extending longitudinally of the tube, all of said edges being connected together whereby the loop slot and hook opening are combined as a single opening with the loop-slot extending circumferentially of the tube and the hook opening portion extending axially thereof.

3. A support for a tapped inductance comprising in combination a supporting tube having in the side wall thereof a loop-slot defined by a side edge extending circumferentially of the tube and an opening for receiving a hook the side edges of which extend longitudinally of said tube, the said side edges being joined together whereby the slot and opening are combined as a single opening with a slot portion thereof extending circum-

ferentially and the hook portion axially of the tube.

4. A support for a tapped inductance comprising in combination, a supporting tube having in the side wall thereof a relatively narrow slot extending circumferentially thereof and a hook opening of less width than the length of said slot extending longitudinally of said tube, the end of said opening extending into a side of said slot.

10 In testimony whereof we affix our signatures.
